FOSTER F. HILLIX, OF CLEVELAND, OHIO, ASSIGNOR, BY MESNE ASSIGNMENTS, TO
WHITE SEWING MACHINE CORPORATION, OF CLEVELAND, OHIO, A CORPORATION
OF DELAWARE.

CORD LOCK.

Application filed December 16, 1922. Serial No. 607,287.

This invention relates to locks for electrical extension cords and has for its object to provide a device which will take the strain off the connection between the wires 5 of the cord and the terminals to which they are connected so as to prevent loosening or breaking of the electrical connections.

A further object is to provide a simple locking device which can be readily slipped 10 upon the cord and fastened in place thereon by means of a simple hand tool so that the lock can be conveniently applied in making connections between the wires of an extension cord and the conductor terminals of 15 the device to which the cord is attached.

With the above and other objects in view, the invention may be said to comprise the devices shown in the accompanying drawings and hereinafter described and particularly claimed, together with such modifications thereof as will be obvious to those skilled in the art to which the invention relates.

Reference should be had to the accompanying drawing forming a part of this specification in which Fig. 1 is a side elevation partially in section showing the cord lock applied to the connection between a cord and the connection plug; Fig. 2 is a sectional view showing the locking member before it is compressed into locking engagement with the cord; Fig. 3 is a sectional view showing the locking member after it has been compressed upon the cord; Figs. 4 and 5 are side elevation and a transverse section respectively showing the device applied to a double cord. Fig. 6 is a detail view of the metal collar and the enclosed sleeve.

Referring to the annexed drawing, the extension cord 1 comprises inner insulated wires 2 and an outer cover or casing 3 of fabric or other suitable material. The locking device consists of an outer sheet metal sleeve 4 which has a small end 5 of a size to fit slidably upon the cord and an enlarged end 6 within which fits a sleeve 7 of compressible and flexible insulating material such as rubber, the internal diameter of 45 which is substantially the same as the internal diameter of the small portion 5 of the outer sleeve. As shown in Fig. 2, the sheet metal sleeve 4 with the rubber sleeve 7 fitting in the enlarged end thereof can

be readily slipped upon the end of the extension cord. By means of a suitable tool a part of the enlarged portion 6 of the sheet metal sleeve is crimped inwardly against the rubber sleeve 7 compressing the sleeve 7 against the cord 1 and firmly locking the device in place upon the cord. The outer edge of the rubber sleeve 7 projects beyond the edge of the enlarged portion 6 of the outer sleeve and when the outer sleeve is crimped inwardly compressing the sleeve 65 7 against the cord, the outer edge 8 of the sleeve 7 projects outwardly and overlies the edge of the sleeve 4 serving to insulate and protect the metal sleeve 4 against electrical contact with the terminals of the connection 70 to which the cord may be attached.

The present invention is applicable to connections between an extension cord and conductor terminals of any fixture or connecting member. In Fig. 1 the cord lock is shown applied to the connection between an extension cord and the connection plug 9. The plug 9 has a pair of terminals 10 to which the wires 2 of the extension cord are attached and carries a cap-shaped cover member 11 which is internally threaded at one end so that it may be screwed upon a threaded portion 12 of the plug and is provided at its opposite end with an inturned flange 13 which surrounds an aperture 14 through which the extension cord passes, the cover 11 together with the plug 9 forming a casing enclosing the connection between the cord 1 and the plug. The cord lock is applied to the cord 1 close to the end 90 which is attached to the plug so that the enlarged portion 6 thereof lies within the cover 11 and bears against the inturned flange 13 of the cover 11. Any pull or strain upon the cord 1 is thus imposed upon the flange 13 of the cover 11 by reason of the engagement of the enlarged portion 6 of the lock therewith and the connections between the wires 2 and the terminals 10 are entirely relieved of such strains so that 100 there is no tendency for the connection between the cord and terminals to work loose or become broken.

Referring to Figs. 4 and 5 in which the cord lock is shown applied to a double cord 105 consisting of a pair of insulated wires 15, the outer metallic sleeve 16 is oval in shape, and has a small end 17 adapted to fit closely

over the wires 15 and an enlarged end 18 within which fits an oval rubber sleeve 19, the sleeves 16 and 19 being otherwise exactly the same as the sleeves 4 and 7 previously described.

Having described my invention, I claim—

The combination with a cord of insulating material having conductors therein, of a rigid collar clamped upon the cord comprising an inner sleeve of compressible in-

sulating material adapted to fit upon the cord and an outer deformable metallic sleeve having one end crimped upon said inner sleeve, its opposite end fitting upon the cord and having a raised circumferential strain 15 relieving bead intermediate its ends.

In testimony whereof, I hereunto affix my signature.

FOSTER F. HILLIX.
